WASHING MACHINE AND VALVE THEREFOR
Rudolph N. Price, 59 Mill Spring Road,
Manhasset, N.Y. 11030
Filed Nov. 22, 1965, Ser. No. 508,984
16 Claims. (Cl. 134—95)

This invention relates to washing apparatus for vials, ampules and the like and more particularly to an improved valve arrangement for use in combination with said washing apparatus.

In my prior patent, U.S. 2,658,011, issued Nov. 3, 1953, apparatus and the method of handling and washing ampules and vials in packed lots is disclosed. The aforementioned patent also reviews in great detail the need for such washing as well as the method of handling both the ampules and the vials. While this will not of discussed herein, a brief description of the environment of this invention will facilitate an understanding of the problems involved and the solution thereto.

A glass manufacturer normally ships ampules to a pharmaceutical company, for example, in one gross cartons containing 9 rows separated by paper board dividers. Each row contains 16 ampules. A rack is placed over a box of ampules and the box is inverted, leaving the ampules arrayed in the rack. The rack containing the ampules is then placed in a washing machine with the open neck of each ampule positioned in opposition to an injector needle. It is also conventional to wash the outside of the vials and drain the wash water to an outlet which also receives the waste injector wash water.

The number and placement of the needless conforms exactly to the number and placement of the ampules. All of the needles together with a mounting plate define a washing head which is replaceable and interchangeable with other washing heads for differently sized and differently placed ampules. A gasket is normally employed to seal the washing head to the housing or "sink." The washing cycle may include a silicon coating step, if desired, and after the washing cycle is completed the rack, together with the ampules, is removed from the machine and the ampules filled by other equipment.

The prior art washers have presented several problems to the pharmaceutical industry. The solenoid valves heretofore used in the washing apparatus regularly developed leaks in service and required frequent and substantial maintenance. In addition, the leakage of the solenoid valves in the "off" position caused partial vaporization of the wash water and, after a period of time, deposition of solids in the washer. The present invention solves the leakage problem and reduces the required maintenance and cleaning by means of a simple yet effective and trouble free structure.

It has been also found that the prior art devices, having a common intake manifold under the needles, do not provide a sufficiently effective drainage system for the wash water. It is essential that complete drainage of the intake manifold be effected because parenteral solutions must be chemically pure and free from contaminating particles. While tap water may be used in the washing cycle, it is important that it does not become mixed with the fluid used in the final rinse. Tap water, of course, contains varying amounts of solids (chemicals) and, if traces of these solids are left in the ampules or vials, the solids will contaminate them and show up as "water marks" after they are dried and ready to be filled.

In order to have the ampule or vial "chemically clean" the manifold under the needles must be completely drained of the prior used washing fluid and either distilled water or steam used in the final rinse. However, large quantities of distilled water are costly and, in some laboratories, not readily available. The present invention ob-

2

viates the need for distilled water by providing complete drainage of the intake manifold. Accordingly, relatively inexpensive and readily available tap water may be used in the final rinse. The apparatus comprising the present invention provides a wash cycle having three basic steps. First, tap water is directed against the ampules. Second, the valve and the intake manifold under the needles is completely drained; third, steam or air is directed against the ampules. In the particular embodiment of the invention, to be described more fully hereinafter, these three steps are repeated once more in the same sequence and then an extra blast of steam is injected to complete a cycle which takes but one minute. Deposition of solids is prevented because the improved drainage system assures that there is no mixing of tap water and steam.

The improved valve used in the present invention is designed (1) to lower the cost of manufacturing the washer; (2) reduce the cost of maintenance; (3) prevent leakage where it normally occurred in the solenoid valves; (4) eliminate the sticky pistons that were usually found after extended periods in the solenoid valves; (5) regulate the flow rate to the manifold under the needles; and (6) regulate and time the injection of wash water for full and complete drainage of the valve and intake manifold.

Accordingly, it is an object of this invention to provide an improved washing apparatus for ampules, vials and the like.

Another object is to provide a more reliable washer of the aforementioned type.

A particular object is to provide an improved drainage system for the washing fluid used in the apparatus.

A feature of this invention is the inclusion of a flapper-type valve that is held closed by the pressure of the incoming water and is automatically opened after a predetermined time to permit complete drainage of the device.

Another feature is the provision of a sloping chamber arranged to direct all of the wash water into a common outlet port.

It is still another object of this invention to provide a washer for ampules, vials or the like that requires less maintenance than prior art devices.

A still further object is to provide a washer of the aforementioned type having an automatic cycle.

Yet another object is to provide an improved washer that operates at high speed and yet is of relatively small size.

It is a particular object of the present invention to provide an improved valve for a washer of the type described.

Another object is to provide a valve that prevents leakage.

An additional object is to provide an improved valve that regulates the flow rate of the liquids and gases to the manifold.

Yet another object is to provide an improved valve that regulates the timing cycle for water, for drainage of the valve and intake manifold and for the injection of steam or air.

These and other features, objects and advantages of the invention will, in part, be pointed out with particularity and will, in part, become obvious from the following more detailed description of the invention, taken in conjunction with the accompanying drawing, which forms an integral part thereof.

In the various figures of the drawing like reference characters designate like parts.

In the drawing:

FIG. 1 is a perspective illustration of a washer incorporating the features of the present invention;

FIG. 1A is a fragmentary sectional elevational view showing the relationship of an ampule and a needle disposed in a washing head;

FIG. 2 is a cross sectional view taken along line 2—2 of FIG. 1, showing in section the valve mechanism and drive means comprising the present invention;

FIG. 3 is a bottom plan view taken along line 3—3 of FIG. 2;

FIG. 4 is a sectional plan view taken along line 4—4 of FIG. 2;

FIG. 5 is a sectional plan view looking upward and taken along line 5—5 of FIG. 2;

FIG. 6 is a sectional plan view taken along line 6—6 of FIG. 2;

FIG. 7 is a fragmentary sectional elevational view taken along line 7—7 of FIG. 3;

FIG. 8 is a fragmentary sectional elevational view showing the valve open and being taken along line 8—8 of FIG. 4;

FIG. 9 is a fragmentary sectional elevational view of a small portion of the cam track;

FIG. 10 is a perspective view of the flapper valve used in the present invention;

FIGS. 11, 12 and 13 schematically illustrate the relationship between the cam means and the outlet orifices at various stages of the washing cycle.

Referring now to FIG. 1, it will be seen that washing apparatus 10 is comprised of a box-like structure 12, commonly known as a sink, and having legs 14 depending from each corner and a cover member 16 hingedly secured on one top edge thereof. Cover member 16 is provided with a hold-down screen 18 that prevents the ampules from blowing off the needles during the washing. The screen is adjustable in height for different sized ampules. Two washing heads 20 may be seen inside the washer and the drive and valve assembly 22 may be seen below the washer housing. FIG. 1A illustrates the manner in which a typical ampule A is placed into position to be washed. By inverting the cardboard container in which the ampules are originally delivered by the manufacturer, the ampules are placed in transfer plate 24 with their open end facing downwardly and resting in a threading plate 26 having a number of conical seats 28. The open end of the ampule is now in opposition to the needle 30 and is ready to be washed. The needles, which are hollow, have their lower ends threaded into a mounting plate 32, such that they are in communication with a manifold 34 formed in the bottommost portion of housing 12. A sealing gasket 35 is also provided. Passageway 36 communicates with the valve and drive assembly 22 now to be described.

Screws 38 (FIG. 3 and FIG. 4) secure the valve assembly 22 to the underside of housing 12. Body portion 40 of the valve assembly is provided with an annular seat for an O-ring 42, so that a cover plate 44, having a central aperture 46 in registry with passageway 36, may be positioned on the underside of housing 12.

The rear side of body portion 40 is provided with a water inlet 48 (FIG. 6) having direct communication, through passageway 50, with water outlet ports 52 and 54. A steam or air inlet port 56 also at the rear of the body portion of the valve assembly communicates, by means of passageway 58, with outlet ports 60, 62 and 64. Each of the five outlet ports just mentioned terminates in an enlarged portion that provides a seat for a resilient O-ring 66 and a Teflon scraper ring 68 (FIG. 2 and FIG. 4). The water outlet ports have scraper rings with relatively large internal diameters 68a, while the steam outlet port scraper rings have smaller inside diameters 68b. This may be clearly seen in FIG. 4. It will be apparent that one very simple means for changing the flow rate of either the liquid or gas is to change the scraper rings so that either smaller or larger inside diameters are provided. The function of the outlet ports will be made apparent in conjunction with the description of the washing cycle.

The rear surface of the valve body portion is also provided with a drainage outlet port 70 which is fed by a sloped central area 71. Of particular interest is the fact that every portion of the central area is directed towards

the outlet port so that complete drainage may be effected. At the appropriate time of the cycle flapper valve 72 is either open or closed. Valve 72 is comprised of a disc-like body portion 74, a pivot arm 76, and a tail portion 78 that lies in a plane slightly above the body portion. In the valve "closed" position the body portion overlies the internal end of the drainage port and is maintained there by the pressure of the incoming water. In the valve "open" position body portion 74 is automatically spaced from the internal end of the drainage port by cam plate 80 which is a disc arranged to be rotated about its own central axis. The cam plate is located in lower chamber 82 formed by the space above the scraper rings and below the cover plate and is formed with three arcuate grooves 84, 86 and 88, all on a common radius. As will be described in more detail hereinafter, the tail portion of the flapper valve is arranged to ride in and out of the three grooves. When the tail portion is in one of the grooves the flapper valve is closed as described above. When the tail portion of the flapper valve is out of the groove and riding along the cam surface in between the grooves, the flapper valve is positively held open for a predetermined time established by the length of the arcuate grooves. It is at this time that drainage takes place. The cam plate is provided with a single aperture 90 positioned on the same radius as the five scraper rings and also a plurality of smaller drain apertures 92 positioned on a common radius somewhat smaller than that of the three grooves. Apertures 92 are located directly over the sloped central portion 71 of the valve body to provide positive and complete drainage whenever the valve opens.

The cam plate is supported on a central shaft 96 that is journaled in the body portion of the valve. O-rings 98 provide sealing means about the shaft, and thrust bearing 100 assures smooth rotation of the cam. The cam shaft further includes an external spur gear 102 keyed thereto in a particular relationship to the cam grooves and the scraper rings. Motor 104, through pinion 106 mounted on the motor drive shaft, actuates the spur gear. The spur gear also includes a pin 108 arranged to engage the lead spring of a snap-action switch 110 when the wash cycle is completed.

Since the spur gear is keyed to the shaft and both the pin 108 and switch 110 are accurately located, the start and stop points of the cycle are precisely determined. The length of the cycle is of course a function of the motor characteristics and gear sizes while the length of each portion of the cycle (water or steam injection and drainage) is determined by the length of the cam grooves and the spaces therebetween.

The cam shaft is held in place by a sleeve 112, a washer 114 and a nut 116. While it is unlikely for a leak to develop as readily as with a solenoid valve, if one does occur, the leak may be stopped by turning the nut to increase the pressure of the cam plate on the Teflon scraper rings. Because the scraper rings have a slippery surface, friction between the rings and cam is minimized even though a considerable force is applied by tightening nut 116. The O-rings 66 assure a good, leak-proof seal.

60

Mode of operation

The mode of operation of the wash cycle will now be described in conjunction with FIGS. 11 through 13. Assuming that the cycle starts with aperture 90 of the cam plate at the three o'clock position, and the cam plate is rotated counter clockwise, the aperture 90 will approach the first water inlet port 52 while groove 84 concurrently approaches the tail of the flapper valve. FIG. 11 shows in solid outline the aperture 90 of the cam plate 80 approaching first water inlet 52 and shows in dot and dash outline the aperture having gone past the inlet 52. The flapper valve body portion is closed against the drainage outlet port during this time and does not open until groove 84 passes the flapper tail portion.

The valve remains open to permit drainage of the

75

water sprayed against the amoles, until the aperture 90 approaches the first steam outlet port 60. At this time, as shown in FIG. 12 in solid outline, the valve closes and remains closed because groove 86 is positioned over the tail of the flapper valve. The valve remains closed until after aperture 90 passes over the second water inlet aperture 54. The dot and dash outline shown in FIG. 12 illustrates the opening of the flapper valve at this time to permit drainage of the water that has collected in the plenum chamber and valve.

The flapper valve automatically closes as the aperture approaches the second steam outlet port 62. This is shown in FIG. 13. The valve remains closed during the continued rotary movement of the complete aperture over the second and third steam ejection ports because the tail of the flapper valve is riding in groove 88. This final position is shown in dot and dash outline in FIG. 13. The valve remains closed until the first groove 84 again approaches the tail of the flapper valve and the aperture 90 in the cam plate once again approaches the first water inlet port 52. The entire cycle takes but one minute and is completed by pin 108 contacting the micro switch.

The apparatus described is compact, rugged and extremely efficient. The operation of the valve is completely automatic and provides the desired cycling of water and steam. Full and complete drainage is automatically provided, as required, after each water injection, so that there is no contamination of the steam that follows. The timing of the drainage cycles may readily be regulated by the use of different cams and the fluid flow rate to the manifold may be regulated by the choice of scraper rings. It will be evident that leakage normally found with the use of solenoid valves is very unlikely with the present apparatus. The structure is extremely reliable and only a minimum of maintenance is required.

Having thus disclosed the best embodiment of the invention presently contemplated, it is to be understood that various changes and modifications may be made by those skilled in the art without departing from the spirit of the invention.

What is claimed is:

1. A rotary control valve for cycling the flow of at least one type of fluid, said valve comprising:
  - (a) a body member having a chamber therein;
  - (b) at least one fluid intake passageway having a first end in communication with the chamber in said body member to define a fluid outlet port, the opposite, second end of said passageway being adapted to receive the fluid to be controlled by said valve;
  - (c) a fluid discharge passageway having a first end in communication with the chamber in said body member and a second end terminating at the exterior surface of said body member;
  - (d) a flapper valve pivotally disposed in said body member in covering relationship to the first end of said discharge passageway, said flapper valve having a tail portion defining a cam follower;
  - (e) a substantially flat cam member rotatably disposed in the chamber of said body member, said cam member having a first aperture arranged to register with the first end of said fluid outlet port, a plurality of second apertures in continuous communication with said fluid discharge passageway and a cam surface arranged to engage said flapper valve tail portion when the first cam aperture is out of registry with the outlet end of said fluid intake passageway; and
  - (f) means to rotate said cam member whereby said cam member aperture is intermittently registered with the outlet port of said body member intake passageway and said cam surface intermittently engages said flapper valve tail portion.
2. The apparatus in accordance with claim 1 wherein said body member includes a plurality of said intake passageways whereby said valve is adapted to control the flow of at least two different fluids.

3. A rotary control valve for cycling the flow of at least two different fluids, said valve comprising:

- (a) a body member having a chamber therein;
- (b) an intake passageway contained in said body member for each of the fluids to be controlled, the first end of each of said passageways being in communication with the chamber in said body member to define fluid outlet ports, the opposite, second end of each of said passageways being adapted to receive the fluid to be controlled by said valve;
- (c) a fluid discharge passageway having a first end in communication with the chamber in said body member and a second end terminating at the exterior surface of said body member;
- (d) a flapper valve pivotally disposed in said body member in covering relationship to the first end of said discharge passageway, said flapper valve having a tail portion defining a cam follower;
- (e) a substantially flat cam member rotatably disposed in the chamber of said body member, said cam member having a first aperture arranged to register with the first end of each of said fluid outlet ports, a plurality of second apertures in communication with said fluid discharge passageway and a plurality of aligned cam surfaces arranged to engage said flapper valve tail portion when the first cam aperture is out of registry with the outlet end of said fluid intake passageway; and
- (f) means to rotate said cam member whereby said cam member aperture is intermittently registered with the outlet ports of said body member intake passageways and said cam surfaces intermittently engage said flapper valve tail portion.

4. The device in accordance with claim 3 wherein said means to rotate said cam member comprises:

- (a) a motor;
- (b) a gear train driven by said motor;
- (c) a shaft journaled in said body member, one end of said shaft being secured to said cam member, the other end of said shaft being driven by said gear train, there being further included sealing means and bearing means interposed between said shaft and said body member.

5. The device in accordance with claim 3 wherein each of said outlet ports is defined by an annular shoulder and wherein there is further included annular, resilient sealing means seated on each said shoulder and an annular orifice member having a low coefficient of friction seated on each said sealing member, said cam member being arranged for sliding engagement with said orifice members.

6. The device in accordance with claim 3 wherein said outlet ports are angularly spaced from each other on a common radius and the first aperture in said cam member is disposed on a radius having a similar dimension to that of said outlet ports.

7. The device in accordance with claim 3 wherein one of said intake passageways for a first fluid is in communication with at least two outlet ports and another of said intake passageways for a second fluid is in communication with at least two other outlet ports.

8. The device in accordance with claim 3 wherein said outlet ports for the two fluids are angularly spaced from each other on a common radius and are arrayed in an alternating pattern.

9. The device in accordance with claim 3 wherein the outlet ports for the first fluid are larger than the outlet ports for the second fluid.

10. The device in accordance with claim 3 wherein said flapper valve comprises: a substantially flat disc portion of sufficient size to cover the first end of said discharge passageway, a pivot member integral with said disc portion, said pivot member being journaled in said body member of said valve and a tail portion integral

with said disc portion and disposed in a plane other than that of said disc portion.

11. The apparatus in accordance with claim 10 wherein said cam surfaces are defined by a plurality of grooves in one face of said cam member, said grooves being arcuate and positioned on a common radius, said grooves being angularly spaced from each other whereby said tail portion of said flapper valve alternately engages a groove and then a flat cam face between said grooves when said cam is rotated, said flapper valve being thereby pivoted between an open position and a closed position with respect to the fluid discharge passageway.

12. Washing apparatus for open ended ampules, vials or the like, said apparatus comprising:

- (A) a housing;
- (B) a threading plate disposed in said housing, said threading plate having a plurality of apertures therein adapted to receive the articles to be washed with the open ends thereof facing downwardly;
- (C) a plurality of hollow elongated needles secured in said housing with the first end of each of said needles spaced opposed to one of the apertures in said threading plate;
- (D) a rotary control valve for cycling the flow of at least two different fluids to the second end of each of said needles, said valve comprising:
  - (a) a body member having a chamber therein;
  - (b) an intake passageway contained in said body member for each of the fluids to be controlled, the first end of each of said passageways being in communication with the chamber in said body member to define fluid outlet ports, the opposite, second end of each of said passageways being adapted to receive the fluid to be controlled by said valve;
  - (c) a fluid discharge passageway having a first end in communication with the chamber in said body member and a second end terminating at the exterior surface of said body member;
  - (d) a flapper valve pivotally disposed in said body member in covering relationship to the first end of said discharge passageway, said flapper valve having a tail portion defining a cam follower;
  - (e) a substantially flat cam member rotatably disposed in the chamber of said body member, said cam member having a first aperture arranged to register with the first end of each of said fluid outlet ports, a plurality of second apertures in communication with said fluid discharge passageway and a plurality of aligned

5

cam surfaces arranged to engage said flapper valve tail portion when the first cam aperture is out of registry with the outlet end of said fluid intake passageway; and

(f) means to rotate said cam member whereby said cam member aperture is intermittently registered with the outlet ports of said body member intake passageways and said cam surfaces intermittently engage said flapper valve tail portion.

10

13. The device in accordance with claim 12 wherein each of said outlet ports is defined by an annular shoulder and wherein there is further included annular, resilient sealing means seated on each said shoulder and an annular orifice member having a low coefficient of friction seated on each said sealing member, said cam member being arranged for sliding engagement with said orifice members.

14. The device in accordance with claim 12 wherein the outlet ports for the first fluid are larger than the outlet ports for the second fluid.

15. The device in accordance with claim 12 wherein said flapper valve comprises: a substantially flat disc portion of sufficient size to cover the first end of said discharge passageway, a pivot member integral with said disc portion, said pivot member being journaled in said body member of said valve and a tail portion integral with said disc portion and disposed in a plane other than that of said disc portion.

16. The apparatus in accordance with claim 15 wherein said cam surfaces are defined by a plurality of grooves in one face of said cam member, said grooves being arcuate and positioned on a common radius, said grooves being angularly spaced from each other whereby said tail portion of said flapper valve alternately engages a groove and then a flat cam face between said grooves when said cam is rotated, said flapper valve being thereby pivoted between an open position and a closed position with respect to the fluid discharge passageway.
